Primary Examiner—Caron D. Veynar

(74) Attorney, Agent, or Firm—Stites & Harbison, PLLC;
David W. Nagle, Jr.(57) **CLAIM**

The ornamental design for a microwave cooking tray, as shown and described.

DESCRIPTION

FIG. 1 is an exploded perspective view of a microwave cooking tray;

FIG. 2 is a top plan view of the lid shown separately for ease of illustration;

FIG. 3 is a top plan view of the cooking tray shown separately for ease of illustration; and,

FIG. 4 is a side elevation view of the microwave cooking tray with the lid closed over the main tray portion. The other side views are identical.
